Fig. 1

Fig. 2

Fig. 3

A technical drawing of a mechanical part, likely a bracket or support. It features a central vertical slot and a flange on the left. Two callout lines point to specific features: line 33 points to a hole near the top of the flange, and line 37 points to a hole near the bottom of the flange. The drawing is labeled 'Fig. 5'.

UNITED STATES PATENT OFFICE.

IWAN SERRURIEE, OF ALTADENA, CALIFORNIA.

PICTURE-PROJECTING APPARATUS.

Application filed February 21, 1923. Serial No. 620,363.

This invention relates to apparatus comprising a cabinet, a picture-projector therein and a screen movably connected with the cabinet, and an object of the invention, in general, is to improve the construction disclosed in United States Letters Patent No. 1,385,955, granted to me July 26, 1921.

Another object of the invention is to mount the screen upon a closure for the cabinet, so that the screen can be closed into the cabinet by shutting of the closure. This distinguishes from the above mentioned patent in that the screen support and the closure were separate members in said patent and did not operate together. Thus I have simplified the construction and operation of the apparatus.

Another improvement is the supporting means for the closure on which the screen is mounted.

The accompanying drawings illustrate the invention:

Figure 1 is a side elevation of an apparatus embodying the invention, the parts being shown in position for projecting pictures upon the screen.

Fig. 2 is a front elevation of the apparatus, the lid being down and the screen being closed into the cabinet.

Fig. 3 is an enlarged fragmental vertical section of the apparatus, the parts being shown in solid lines in the positions they occupy in Figure 2, and the screen and its supporting means being shown in broken lines in the positions they occupy when the support is elevated and the screen is collapsed.

Fig. 4 is an enlarged sectional detail of the support and screen in the same position as in Figure 3.

Fig. 5 is an enlarged sectional detail of the latch for the bracket that holds the support in open position.

Fig. 6 is an enlarged elevation of the apparatus from the right of Figure 1, the lid being omitted.

Fig. 7 is a sectional elevation similar to Figure 3, excepting that the screen and its support are in the same positions as in Figures 1 and 6.

Fig. 8 is an inverted plan view of a portion of Figure 7.

There is provided a cabinet 11 of any suitable construction and said cabinet is provided with a hinged lid 12 adapted, when closed, to cover the projector 13, which is mounted on the cabinet. The lid, however, is not essential and may be omitted. The

cabinet 11 is provided in its front with a recess 14 and, if it is desired to separate said recess from other portions of the interior of the cabinet, this may be done by a partition, 60 indicated at 15. Such partition, however, is not necessary, but it adds to the appearance of the apparatus when the recess closure, indicated at 16, is in position to disclose the recess.

The closure 16 is movably mounted, being hinged at its upper edge at 17 to the cabinet 11, and constitutes a vertically swinging door for the recess. Not only does the door 16 serve to close the recess, but it also functions, when elevated, as in Figure 1, as a support for a screen 18. The screen 18 is preferably collapsibly mounted on the door and, in this instance, is hinged at 19 to that face of the door that is undermost when the door is raised and that is turned inwardly when the door is closed. The hinges 19 comprise brackets 20, secured to the inner face of the door 16, and L-shaped arms 21 secured to the side edges of the screen. The arms 21 enable the screen 18 to be swung into position abutting the outer end of the door 16 as in Figure 1 so as to project the screen into position above the level of said door and in axial alignment with the projector when the door is open or horizontal.

To yieldingly hold the screen 18 in its open or elevated position coil springs 22 are secured at one end to the edge of the screen 18 that is nearest the hinge 19, and the other ends of the springs 22 are connected to the under face of the door 16 so that when the screen is in open position, as in Figure 1, the springs will be under tension and therefore tend to hold the screen open against the edge of the door, which edge thus constitutes an abutment to limit movement of the screen towards the projector. When the screen 18 is swung into closed position, as in Figure 4, the springs lie between the screen and the under face of the door.

Means are provided to hold the screen in its collapsed position and, though any suitable means may be employed for this purpose, I have shown in the drawings an L-shaped latch 23 pivoted at 24 to the under face of the door, one end of the latch 23 having a shoulder 25 adapted to engage the edge of the screen 18, and a spring 26 yieldingly holding the latch 23 in its screen-engaging position. To release the screen 18, the latch 23 will be operated against the

pressure of the spring 26 to retract the shoulder 25 from engagement with the screen, thus permitting the screen to swing downwardly from the door. Then, to place the

5 screen in position for use, the operator will swing the same outwardly and upwardly against the tension of the springs 22.

Means are provided to support the door 16 in its elevated position and, though such 10 means may be variously constructed, I have shown in the drawings the construction at present employed. This construction is as follows:

Arms 27, that converge downwardly and 15 inwardly when the door is elevated, are pivotally connected or hinged at 28 to the inner face of the door 16. The hinge, in this instance, comprises a rod 29 supported by ears 30 affixed to the inner face of the door. The 20 arms 27, if desired, may be connected at their divergent ends by a brace 31. Through the convergent ends of the arm 27 extends a pin 32 which operates in a slot that 25 comprises two ways or limbs 33, 34, there being a shoulder 35, at the intersection of the limbs 33, 34, to constitute an abutment, 30 against which the pin 32 seats when the door is in open position, as in Figure 7. To close the door, the operator will elevate the rear 35 ends of the arms 27, thus moving the pin 32 away from the abutment 35 and into the limb 33 of the slot. It will be noted that the shorter limb 34 of the slot is nearer the 40 swinging member or closure 16, thus preventing shutting of the closure unless the operator grasps one of the arms 27 with one hand and forces it inwardly after having raised the closure with the other hand. This construction avoids accidental closing of the 45 member 16 in case said member is inadvertently raised or knocked upwardly. The operator then allows the door to close and this causes the pin 32 to travel downwardly in the slot. To open the door and latch the 50 same in its open position, the operator will raise the door as high as possible and, when the pin 32 travels from the upper end of the slot limb 33 into the limb 34, gravity causes the arms to drop to seat the pin against the shoulder. The slot 33, 34 may be constructed 55 in any suitable manner and, in this instance, is formed in part by a slotted casting 36 and in part by a metal strip 37 and the partition 15, the strip 37 being spaced from the partition and secured at one end to the casting 36 and at its opposite end to the floor 38 of the recess 14.

When it is desired to project pictures onto the screen, the door will be opened and the 60 screen elevated in a manner hereinbefore described so as to position the screen in front of the projector 13, as in Figure 1.

If desired, the door 16 may be releasably held in closed position by one or more of 65 the well known ball catches indicated at 39.

These ball catches are well known in the cabinet maker's art and it is therefore unnecessary to illustrate and describe them in detail herein.

I claim:

1. In a picture-projecting apparatus, the 70 combination of a cabinet having a recess in its front, a picture-projector on the cabinet, a closure for the recess, means to hold the closure in open position, and a screen connected with the closure movable from position along the inner face of the closure to position in front of the projector when the closure is open.

2. In a picture-projecting apparatus, the 80 combination of a cabinet, a picture projector supported by the cabinet above the top thereof, a closure for the cabinet, a screen, and means operable to effect movement of the screen into the cabinet below the level of the projector by shutting of the closure and to effect movement of the screen out of the cabinet by opening of the closure, said means 85 permitting the operator to position the screen in axial alinement with the projector 90 when the closure is open.

3. In a picture-projecting apparatus, the 95 combination of a cabinet, a picture projector supported by the cabinet above the top thereof, a door for the front of the cabinet, and a screen mounted on the inner face of the door and adapted to be moved into position to receive an image directly from the projector when the door is open.

4. In a picture-projecting apparatus, the 100 combination of a cabinet, a picture projector supported by the cabinet, a vertically swinging closure for the cabinet, a screen hinged to the inner face of the closure and movable into position against the outer edge 105 of the closure, and means to hold said screen against said edge.

5. A picture-projecting apparatus comprising a cabinet, a picture projector supported in the upper portion of the cabinet, 110 a closure for the lower portion of the cabinet adapted to swing downwardly and inwardly into closed position, a screen, and means connecting the screen to the closure and operating to hold the screen in position to project upwardly from the closure when the closure is open and to lie along the inner face of the closure when the closure is shut. 115

6. In a picture-projecting apparatus, the 120 combination of a cabinet having a recess, a picture projector mounted on the cabinet, a support hinged to the cabinet to swing vertically and adapted to close into the recess, a screen movably mounted on the inner face of the support and adapted to be moved into position in front of the projector when the support is horizontal, and means to releasably hold the support in horizontal position.

7. The combination of a stationary member, a vertically swinging member hinged to 125

the stationary member, an arm pivotally connected at one end to the under face of the hinged member and provided at its other end with a pin, there being a groove in the stationary member for the pin to travel in and said groove having intersecting limbs of different lengths, the shorter limb of the groove being nearer the swinging member than the longer limb, and a shoulder at the intersection of the groove limbs forming an abutment for the pin to rest against when the hinged member is swung away from the stationary member.

10 8. In a picture-projecting apparatus, the combination of a stationary member, a vertically swinging member hinged to the stationary member, an arm pivotally connected at one end to the under face of the hinged member and provided at its other end with a pin, there being a groove in the stationary member for the pin to travel in and said groove having intersecting limbs of different lengths, the shorter limb of the groove

being nearer the swinging member than the longer limb, and a shoulder at the intersection of the groove limbs forming an abutment for the pin to rest against when the hinged member is swung away from the stationary member.

15 9. A picture-projecting apparatus comprising a cabinet, a picture projector supported by the cabinet, a closure adapted when open to project laterally from the cabinet and to swing downwardly and inwardly into closed position, a screen, and means 30 foldably connecting the screen to the closure and operable to hold the screen elevated in front of the picture projector when the closure is in open position and to permit the screen to be folded into position beneath the 35 laterally projecting closure so that when the closure is shut, the screen will be positioned inside of the cabinet.

Signed at Los Angeles, California this
14th day of February, 1923.

IWAN SERRURIER.
